(57) **CLAIM**

I claim the ornamental design for a travel jewelry bag, as shown and described.

DESCRIPTION

FIG. 1 depicts a top perspective view of a travel jewelry bag of the present invention, showing my new design;

FIG. 2 depicts a front view thereof;

FIG. 3 depicts a rear view thereof;

FIG. 4 depicts a top view thereof;

FIG. 5 depicts a bottom view thereof;

FIG. 6 depicts a left side view thereof; and,

FIG. 7 depicts a right side view thereof.

The broken lines illustrate portions of the travel jewelry bag and form no part of the claimed design.
